W. C. SLEEMAN

REVERSIBLE BRAKE SHOE HEAD

Filed Oct. 12, 1927

INVENTOR
WILLIAM C. SLEEMAN.
BY D. Anthony Meiss
ATTORNEY

UNITED STATES PATENT OFFICE.

WILLIAM C. SLEEMAN, OF BIRMINGHAM, ALABAMA.

REVERSIBLE BRAKE-SHOE HEAD.

Application filed October 12, 1927. Serial No. 225,873.

This invention relates to improvements in or relating to railway car construction and has particular reference to brake heads adapted to be secured to the ends of brake beams. The invention aims to provide a reversible brake shoe head which is so constructed that it can be applied to either end of a brake beam so as to avoid the necessity of using right and left hand brake shoe heads. The invention will be apparent from the following specification when read in connection with the accompanying drawings and will be defined with particularity in the appended claims.

15 In the drawings—

Fig. 1 is a plain view of the brake beam having my improved brake heads attached to the opposite ends thereof;

Fig. 2 is a cross-section on line 2—2 of Fig. 1 illustrating the head secured to the right-hand end of the brake beam;

Fig. 3 is an enlarged horizontal section of the right-hand end of Fig. 1, the section being taken on the plane of the line 3—3 shown 25 in Fig. 2.

Referring in detail to the drawings, the brake beam includes the usual compression member 10, tension member 12 and central fulcrum or strut 14. At the ends the compression and tension members are secured to brake shoe heads 16 which are of identical construction so that one design of head can be used for either end of the brake beam thus avoiding the necessity of providing rights 30 and lefts. Inasmuch as the two brake heads 16 are identical, a detailed description of one will suffice for both.

In the embodiment of the invention illustrated, the compression member 10 is in the form of a channel or U-shaped beam and the tension member is in the form of a rod or bar of round cross-section.

My improved reversible brake head includes a heel portion 18 having a central web 20 and oppositely extending upper flanges 22 and lower flanges 26 which are adapted to engage the horizontal flanges 24 and 25 of the compression member. The heel of the brake head also includes rear flanges 28 and 30 which engage the vertical web of the compression member 10 and flange-like portions 32 and 34 which engage the edges of the flanges 24 and 25 of the compression member.

55 The heel of the brake head also includes a

body portion 36 which is adapted to extend into the space between the flanges 24 and 25 of the compression member 10. This design of the brake head provides channels or U-shaped pockets 38—38 on each side of the web 20. These pockets it will be apparent are of a contour which matches the cross-sectional contour of the channel or U-shaped compression member. Inasmuch as the brake head is formed symmetrically on each side of its center web 20, it is apparent that such a brake head can be applied interchangeably to either the right-hand or left-hand end of compression member of the brake beam. The inwardly projecting member 36 of the brake head is of hollow or skeleton form and is apertured as indicated at 40 and 42 to permit the passage therethrough of the tension member 12. Bearing faces 44—44 are provided which are substantially perpendicular to the axis of the apertures 40 and 42. These bearing faces are provided, of course, to form flat seats for the nuts 46 threaded on the ends of the tension member. The brake heads are provided with suitable base portions 48 shaped to fit standard or conventional forms of brake shoe. From the foregoing, it is clear, that the brake head illustrated and described can be interchangeably used on brake beams facing in different directions, said head being adapted for use on either the right or left-hand end of either a live brake beam or dead brake beam.

While I have described quite specifically the embodiment of the invention illustrated, it is to be understood that modifications may be made without departing from the invention as defined in the appended claims.

What I claim is:—

1. In combination with a brake beam having compression member, tension member and strut, a reversible brake shoe head adapted to be secured to said compression and tension members at either end of the beam, said head having seats on the opposite sides of the center line to receive the end of the compression member and also having oppositely inclined apertured portions for engagement with the tension member of the brake beam.

2. In combination with a brake beam having a channel shaped compression member and a rod-like tension member, a brake shoe head having respective duplicate seat portions symmetrically arranged on opposite

sides of the center line thereof for coaction respectively with said compression and tension members.

3. In combination with a brake beam having a compression member and a tension member, a brake shoe head having respective duplicate seat portions symmetrically arranged on opposite sides of the center line thereof for coaction respectively with said compression and tension members.

4. A brake shoe head adapted to be interchangeably secured to either end of a brake beam, said head having symmetrically arranged on each side of the center line thereof a socketed portion for engagement with the compression member of the brake beam and an apertured portion for engagement with the tension member of the brake beam.

5. A brake shoe head adapted to be interchangeably secured to either end of the brake beam having a substantially U-shaped socketed heel portion on each side of the head for co-operation with a compression member

of the brake beam and also having on each side an angularly disposed apertured portion for coaction with the tension member of the brake beam.

6. The brake head of claim 5 characterized by the provision of an inclined seat, the bearing surface of which is substantially or approximately perpendicular or normal to the axis of the angularly disposed opening in said apertured portion.

7. In combination with a brake beam having a compression member and a tension member, a brake shoe head having respective seat portions arranged on opposite sides of the center line thereof for coaction respectively with said compression and tension member and means secured to the tension member arranged to hold the head in engagement with said compression member.

In witness whereof, I have hereunto signed my name.

WILLIAM C. SLEEMAN.
